United States Patent Office.

EDWARD SEALY, OF NEWARK, NEW JERSEY.

Design No. 2,828, dated November 5, 1867.

DESIGN FOR A BAND-SLIDE.

The Schedule referred to in these Letters Patent and making part of the same.

TO ALL WHOM IT MAY CONCERN:

Be it known that I, EDWARD SEALY, of Newark, in the county of Essex, and State of New Jersey, have invented or produced a new and original shape and configuration of the article of manufacture known as a Slide for a Hat-Band, and that the following, taken in connection with the accompanying drawing, is a description of the same.

The novel shape or configuration of slide for a hat-band, which I have produced, as represented in the accompanying drawing, is a perforated lozenge figure, of thin metal, A, in breadth about equal to that of the band, to which it is secured (by preference) by sewing, for which mode of securement the new slide presents great facilities, as the sewing can be effected through the perforations. I also prefer to curve the slide, so as to make it set more closely to the hat-band to which it is sewn.

I claim the design for a perforated lozenge-shaped slide for a hat-band, described and represented. In testimony whereof I have hereto set my hand this third day of August, 1867.
